UNITED STATES PATENT OFFICE.

CHARLES E. DAVIS, OF CHICAGO, ILLINOIS, ASSIGNOR TO GOODMAN MANUFACTURING COMPANY, OF CHICAGO, ILLINOIS, A CORPORATION OF ILLINOIS.

CHAIN FOR MINING-MACHINES.

Specification of Letters Patent. Patented Aug. 23, 1910.

967,884.

Application filed March 10, 1910. Serial No. 548,447.

To all whom it may concern:

Be it known that I, CHARLES E. DAVIS, a citizen of the United States, residing at Chicago, in the county of Cook and State 5 of Illinois, have invented a certain new and useful Improvement in Chains for Mining-Machines, of which the following is a specification.

This invention relates to cutter chains for 10 mining machines, and has for its object to provide a new and improved device of this description.

The invention is illustrated in the accompanying drawings wherein—

15 Figure 1 is a plan view showing a portion of a chain embodying the invention; Fig. 2 is a plan view of one of the cutter blocks; Fig. 3 is a front view of one of the links by which the chain blocks are connected; Fig. 20 4 is a sectional view through the chain showing it in position in the cutter head of a mining machine; Fig. 5 is an end view of one of the chain straps.

Like numerals refer to like parts throughout the several figures.

In the drawings I have shown a cutter chain for mining machines. This chain is made up of a series of chain blocks 1 pivotally connected together by a series of 30 straps 2. The chain in use is an endless chain and passes about a sprocket wheel and works in a groove. This groove is provided at the top and bottom with guideways 3 (see Fig. 4), in which the restraining lips 4 35 and 5 on the block and strap move. The blocks are provided with cutters 6, some of which in practice are inclined so as to be at an angle, as shown in Fig. 4. When these cutters are cutting the coal, there is a strain 40 on the chain which is taken up by the lips 4 and 5, said lips engaging stop pieces 7 at the front of the chain groove, which stops hold the chain in place. It will be noted that some of the cutters are at one side of 45 the point where the chain is confined, and that these cutting points are in a plane out of the center of the chain block and therefore there are two twisting actions when the device is in operation, one in a vertical plane 50 and the other in a horizontal plane. The twist in the vertical plane causes an uneven wear on the guiding and restraining lips 4 and 5, wearing them to a beveled face and making them narrower at the outer edge,

that is at the top and bottom. The horizontal twist causes a wear at one end of the lip and also a wear on the back of the block at the opposite end. In the present case this wear is minimized by moving the points where the straps are connected to the chain 55 blocks forward toward the point of the cutter, and by a proper arrangement and position and size of the restraining lips 4 and 5. It will be noted that the guiding and restraining lips are approximately evenly distributed between the blocks and the straps. The guiding and restraining lips of the blocks are of such length that the ends thereof project beyond the adjacent faces of the holes by which the links are connected to 60 the blocks, that is, such lips are greater in length than the distance between the adjacent sides of such holes. The lips on the straps are beveled at 8, so as to produce inclined faces inclining toward the back of the 65 chain. The length of the lip 5 on the chain strap is less than the distance between the adjacent sides of the rivet holes therein, and the front or working face of said lip is back 70 of the external face of the lugs 9 on the strap by means of which it is connected to the block. The distance between the ends of the lips on the straps and the centers in the blocks, about which the straps rotate, is such 75 that the ends of the lips on the straps never project forward of the front faces 10 of the 80 lips on the chain blocks when the straps are moved about these centers during the operation of the device.

I have found that with this construction 90 the chain wears very much longer than the chains ordinarily used.

It will be noted that the restraining lips 4 and 5 are back of the holes in the blocks and straps, and that the strain and wear 95 comes upon the front faces of these restraining lips, which are comparatively small in area. It will further be noted that the front faces of the restraining lips on the blocks are substantially equal in length to the rear 100 faces of the restraining lips on the straps.

I claim:

1. A chain for mining machines comprising a series of chain blocks having holes therethrough, a series of chain straps connected with said blocks, at the points where said holes are located, restraining lips on the chain blocks, back of said holes, the front

face of said restraining lip being longer than the distance between the adjacent faces of the holes in the block.

2. A chain for mining machines comprising a series of chain blocks having holes therethrough, a series of chain straps connected with said blocks, at the points where said holes are located, restraining lips on the chain blocks back of said holes, the front faces of the restraining lips being longer than the distance between the adjacent faces of the holes in the blocks, and restraining lips on said straps beveled at the ends so as to produce inclined faces inclining toward the back of the chain, said inclined faces adapted to engage the ends of the lips on the blocks to limit the backward movement of the straps.

3. A chain for mining machines comprising a series of chain blocks having holes therethrough, a series of chain straps, projecting lugs on said straps which fit into the holes in the blocks, the lugs in the straps provided with holes into which fastening devices are received, restraining lips on the chain blocks back of said holes, the front faces of the restraining lips being longer than the distance between the adjacent faces of the holes in the blocks, and restraining lips on said straps shorter in length than the distance between the adjacent sides of the holes in the straps.

4. A chain for mining machines comprising a series of chain blocks having holes therethrough, a series of chain straps, projecting lugs on said straps which fit into the holes in the blocks, the lugs in the straps provided with holes into which fastening devices are received, restraining lips on the

chain blocks, and straps, back of said holes the length of the front faces of the restraining lips on the blocks being substantially equal to the length of the rear faces of the restraining lips on the straps.

5. A chain block for mining machine chains adapted to receive a cutter and provided with holes for connecting it to adjacent parts, a lip on said block back of said holes, the front face of said lip being greater in length than the distance between the adjacent sides of said holes.

6. A chain for mining machines comprising a series of chain blocks adapted to receive the cutters, a restraining lip on each of said blocks, a series of straps connecting said blocks together, said straps pivotally connected with said blocks, restraining lips on said straps, the distance between the adjacent ends of the restraining lips on the adjacent straps and blocks, at their working faces, and the centers about which the straps move, being substantially equal.

7. A strap for mining machine chains provided at each end with projecting lugs, said lugs having holes therethrough, a restraining lip on said strap having its working face back of the external faces of said lugs and shorter in length than the distance between the adjacent faces of said holes, the ends of said lip beveled so as to provide inclined faces thereon, inclining toward the back of said strap.

Signed at Chicago, Illinois, this 11th day of February, 1910.

CHARLES E. DAVIS.
